FASTENER AND ORNAMENTATION DEVICE

Guy H. Montmartin, New York, N. Y.

Application June 30, 1941, Serial No. 400,593

12 Claims. (Cl. 24—73)

This invention relates to the art of fasteners and ornamental devices. More particularly, it pertains to a device which may be broadly identified as of the snap-fastener variety which is novel relative to structural aspects and from the standpoint of ornamentation.

In the fastening art, notwithstanding the numerous devices available, there is a dearth of means which combine operative simplicity with sturdiness of construction, and esthetic value with general utility. The usual types of fastening devices, especially of the so-called snap-fastener variety, are essentially devoid of ornamentation value and too frequently are unreliable in their function, due to the fact that small changes in the structure of the socket portion, such as results from injury thereto or slight spring failure, renders them ineffective and/or uncertain. Efforts to obviate these uncertainties have resulted in structural complications which have at the same time detrimentally affected their esthetic significance. Moreover, as a device of general utility, the snap-fastener does not lend itself to flexibility of application, since it is normally restricted to but a single manner of attachment.

It is an object of my invention to obviate such difficulties and uncertainties as hereinabove described.

An additional object is to provide a fastener of simple, sturdy construction adapted to function in the snap-on manner.

Another object is to obtain a fastener device which lends itself to diversified types of attachment.

An important object is to devise a fastener device which combines novelty of structure with novelty of ornamentation.

A further object is to present a new ornamentation device.

Other objects, advantages, and features of my invention will become apparent from the following description to be read in connection with the accompanying drawing, in which similar elements are designated by like numerals:

Figure 1 shows in front elevation the component parts of the invention, the spherical members being partially broken away;

Fig. 2 is a side elevation of Figure 1;

Fig. 3 presents a front view of the fastener assembly in association with the parts of a garment, the fabric being shown in fragmentary portions;

Fig. 4 is a cross-sectional view taken along 4—4 of Fig. 3;

Fig. 4a provides a cross-sectional view similar to that of Fig. 4, indicating an alternative form of attachment;

Fig. 5 relates to a modification showing a concave convex contact between the ornamental means and complementary member.

Referring more particularly to the adaptation of the invention as presented by the desirable embodiment shown on the drawing, the numeral 1 designates an extensible-retractable element in the form of a coil spring, preferably closely wound and manifesting a reasonable degree of resilient or elastic tension. The ends of the spring means are compactly bound together as by appropriate overlapping 2 to provide an endless coil of substantial elasticity; in lieu of overlapping, tying, welding, etc. may be resorted to. Mounted upon said coil 1 through suitable openings or perforations 3 are a plurality of spherically shaped elements, hollow or otherwise, which are desirably positioned contiguous to each other in usual bead fashion.

Affixed to the outer periphery of one of said spheres 4 is a flexible means 5 expediently in the form of a chain. The other extremity of chain 5 is attached to plate support 6, conveniently at an edge of said plate. The manner of attaching the chain extremities to the sphere and plate respectively is essentially a matter of choice within the skill of one versed in the art; as shown, one end is connected to half link 7 integral with an aforementioned sphere 8, while the other end closes a link through perforation 9 of plate 6.

Integral with plate 6, which may be of circular configuration, and substantially centrally positioned thereon, is a shank or projection element 10 provided with a spherical head 11, desirably of somewhat greater diameter than spheres 4. This shank and head assembly constitutes in effect a stud means upon which the socket portion of the device, such as the coil spring circlet, may be impaled.

Referring particularly to Figs. 3 and 4, 12 and 13 designate fragmentary portions of a garment fabric, such as a lady's coat, to exemplify the utilization of a device as a fastening means. Plate 6 may be attached to fabric 12 superficially as by stitching through openings 14 on said plate. Fabric 13 is provided with a button hole or the like 15 through which the coil spring circlet may be passed from the inside of the garment outwardly for a snap-over association with head 11. To facilitate the passage of the circlet through the button hole 15, it is merely necessary

to laterally compress said circlet, thereby temporarily distorting the same longitudinally.

Alternatively to the surface attachment of plate 6 to the fabric, the head 11 may be thrust through an appropriate opening 16 on fabric portion 12 from the direction of the inner surface of the garment, as shown in Fig. 4a. Since the diameter of plate 6 is substantially greater than that of the head means 11, stitching of the plate to the inner surface of the fabric may be optional in this arrangement. The extensible circlet may be passed through opening 15 for association with head 11 in precisely the same manner as indicated hereinabove.

An additional illustrative manner of attachment of plate 6 to the fabric is between the layers of a "split" lining or between the liner and surface fabric.

It will thus be seen that the circlet functions similarly to the socket portion of a snap-fastener with head 11 serving as the complementary male portion upon which the circlet is impaled in a manner to provide a retaining contact engagement. The dimensioning of the various elements of the device will be subject to variation in accordance with preference as well as the dictates of any given circumstances of usage. Thus it should be noted that the diameter of head 11 taken together with the length of projection or shank 10 should be such that when plate 6 is in any predetermined position of usage, the circlet will be of a diameter to positively and circuitously engage head 11, the point of contact of said spheres 4 with head 11 being along the surface of the spherical head member between the center of the latter and plate 6, as shown in Fig. 4, to desirably provide a stable association or locking expedient between the circlet and the complementary male portion or stud member.

The possibilities afforded by the invention for novelty of ornamentation need no detailed elucidation and will depend upon the design and configuration of the component parts of the device. It will be seen that the modification shown in Figs. 1-4 provide an esthetic cluster. While a primary adaptation of the device is in the form of a fastener, it lends itself to use as an ornamentation per se. For example, the invention may be applied to the button hole of a coat lapel or to my lady's hat, with excellent effects. As in the case of its utilization as a fastener, it may be attached as an ornamental device by affixing supporting plate 6 to the object of adornment, or by protruding the means 10 with head member 11 through an appropriate opening and bringing the circlet over for engagement with said head member.

While the desirable embodiment of the invention shown in Figs. 1-4 indicates the use of spheres to constitute the circlet, the invention is not restricted to this configuration and clearly lends itself to many ramifications. For example, elements 4 may well be of cylindrical shape and mounted on their transverse or longitudinal axis for association with any appropriate supplementary contact means. Illustratively, they may be mounted along their transverse axis and adapted to form an ornamental cluster with a comparatively enlarged contact cylinder replacing the shank 10 and its spherical head 11. If desired, any locking expedient may be resorted to, such as the provision of an enlarged or bulbous head portion on the contact cylinder or by resort to interfitting elements.

In lieu of the point contact between the spheres and spherical head member, the objects mounted on coil spring 1 may be provided on their surface facing said head member with a concavity 17 adapted to fittedly seat or nest against the surface of said head member; differently stated, the radius of the concave portion should correspond with the radius of the head member with which it is in contact, as shown by Fig. 5.

The particular material from which the various parts may be fabricated has no critical bearing upon the invention and will doubtless be determined largely from expediency and preference. Thus, while coil spring 1 may be of steel, and spheres 4, head 11, projection 10, plate 6 and chain 5 may be of appropriate metal, these elements need not necessarily be of such material. Illustratively, 1 may be an extensible or elastic band or cord; spheres 4, projection 10, head 11, 20 may be of a plastic composition; while resilient element 5 may be a cord of leather or otherwise. As a suggested alternative for a button hole 15, a conventional cord loop may be utilized.

It will thus be seen that the device forming the basis of the invention, as illustrated by the embodiments above considered, provides an expeditious means for functioning as a separable fastener device which affords facility and efficiency in operation, sturdiness of construction, as well as distinct novelty of ornamentation.

While I have described my invention in accordance with desirable embodiments, it is obvious that many changes and modifications may be made in the details of construction and in the combination and arrangement of parts without departing from the spirit of the invention as defined in the following claims.

I claim:

1. In a separable fastener device, a socket member and a complementary element for impaling engagement by said socket member, said socket member comprising an endless extensible-retractable means and means mounted thereon for engaging contact with said complementary element.

2. The device which comprises a socket member, a complementary element for impaling engagement by said socket member, and a flexible means for connecting said complementary element to said socket member, said socket member comprising an endless spring coil and means mounted on said coil for retaining contact engagement with said complementary element.

3. In a separable fastener and/or ornamental device, a socket member, a supporting plate means integral with a complementary contact element, and a flexible means for connecting said supporting plate with said socket member and adapted to consummate the fastening between said socket member and complementary element, said socket member comprising an endless spring coil and means mounted on said coil for retaining contact engagement with said complementary element.

4. In a separable fastener and/or ornamental device, an endless extensible-retractable member, means positioned on said coil member contiguously to each other and adapted for retaining contact engagement with a complementary contact element, a supporting plate integral with a complementary contact element, and a flexible means for connecting said supporting plate with one of said means positioned on said coil member and adapted to consummate the fastening between said coil member and complementary

element, said complementary element comprising stud means integral with and approximately centrally positioned on said supporting plate.

5. In a separable fastener and/or ornamental device, an endless extensible-retractable coil member, a plurality of spherical means positioned on said coil member contiguously to each other and adapted for retaining contact engagement with a complementary contact element, a supporting plate integral with a complementary contact element, and a chain for connecting said supporting plate with one of said spherical means positioned on the coil member and adapted to consummate the fastening between said coil member and complementary element, said complementary element comprising a spherically curved surface means integral with and approximately centrally positioned on said supporting plate.

6. The combination as in claim 5 wherein the contact between the respective surfaces of the spherical means mounted on the coil and the spherically surfaced complementary contact element is substantially tangential at points between the center of said contact element and said supporting plate.

7. The combination as in claim 5 wherein the contact between the spherical means mounted on the coil and the spherically surfaced complementary contact means is substantially concave-convex.

8. A device comprising a complementary contact member, an endless spring coil having means of any predetermined contour mounted thereon for impalement on and providing a cluster contact with said complementary contact member, and a flexible means connecting said member with said endless coil through one of said means mounted on said coil.

9. A device comprising a complementary con-

taught member of spherical contour supported on and integral with a plate means, an endless spring coil having means of spherical contour mounted on said coil for impalement on and providing a cluster contact with said complementary contact member, and a chain connecting said plate means with said endless coil through one said spherical means mounted on said coil, said spherical means on said coil being adapted for retaining contact with said complementary member at points between the center of said complementary member and said plate means.

10. In a cooperating stud and socket fastener device, a stud means and a socket for impalement thereon, said socket comprising an elastic circlet having a plurality of curved surface means mounted thereon, said socket being adapted for interlocking contact on said stud means.

11. In a cooperating stud and socket fastener device, a curved surface stud means having a base member, a socket for impalement thereon comprising a coil spring circlet having a plurality of curved surface means mounted thereon contiguous each other, said circlet being adapted for interfitting engagement with said stud means, and a flexible means affixed at one end to said base member and at its other end to said circlet.

12. In a cooperating stud and socket fastener device, a stud means having a spherical head, shank and base member, a socket for impalement thereon comprising a retractable coil spring circlet having a plurality of spheres mounted thereon and contiguous each other, said circlet being adapted for contact of its spheres with said spherical head at points between the center of said head and said stud base member.
